WATER PUMP DEVICE

Greek S. Shupe, Fort Stockton, Tex.

Application July 1, 1940, Serial No. 343,477

1 Claim. (Cl. 103—212)

This invention aims to provide a simple means whereby the piston of a pump in a well can be operated without the use of pump rods, it being possible to raise the pump piston by means of a simple flexible element, novel means being provided for giving the piston a downward stroke. Another object of the invention is to provide novel means whereby the piston and associated parts can be raised readily out of the pump line.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in vertical longitudinal section, a device constructed in accordance with the invention;

Fig. 2 is a vertical longitudinal section at right angles to the cutting plane in Fig. 1;

Fig. 3 is a view similar to Fig. 1, but showing a piston and associated parts at the limit of the upstroke;

Fig. 4 is a vertical longitudinal section showing the latches disengaged from a shoulder in the pump line, by means of a latch release on the piston rod;

Figs. 5 and 6 are sections taken, respectively, on the lines 5—5 and 6—6 of Fig. 4;

Fig. 7 is a fragmental longitudinal sectional view illustrating details connected with the latch release;

Fig. 8 is an elevation showing a slight modification.

In carrying out the invention, there is provided a pump line P, including a pipe 1, joined by a coupling 2 to a cylinder 3 having a bottom intake 4 controlled by a check valve 5, the lower end of the pipe 1 forming a shoulder 6 within the coupling 2.

A valved piston 7, of the usual construction, or of any preferred construction, is mounted for reciprocation in the cylinder 3 and is secured to the lower end of a piston rod 8. To the upper

end of the piston 8 is connected a flexible element 9, which functions to raise the piston 7.

At this point it should be noted that, as hereinafter described, a means is provided for moving the piston 7 downwardly, and, therefore, a long string of pump rods, which is inconvenient to handle, and costly to make, may be dispensed with, the simple flexible element 9 being substituted.

The numeral 10 marks a transverse guide, wherein the piston rod 8 reciprocates. Latches 11 are pivotally mounted intermediate their ends, as shown at 12, on the guide 10, on opposite sides of the piston rod 8. Any suitable means may be provided for holding the upper portions of the latches 11 releasably engaged beneath the shoulder 6. For example, the lower portions of the latches 11 may be drawn toward each other by a pull spring 14 which connects them. It is not necessary, however, that the pull spring be used. Referring to Fig. 8, one of the latches is shown at 11a and is enlarged at its lower end to form a weight 15, both latches being fashioned in that manner.

The numeral 16 marks a frusto-conical latch release, held by a set screw 17 in adjusted positions longitudinally of the piston 8, the latch release being located beneath the latches 11.

As a means for carrying the piston rod 8 and the piston 7 downwardly, there is provided a pull spring 18 having its upper end connected by a set collar 19 to the upper portion of the piston rod 8, the lower end of the spring being secured at 20 to the guide 10. The spring 18 not only carries the piston rod 8 and associated parts downwardly, but also exerts an upward pull on the guide 10 and, in turn, keeps the upper ends of the latches 11 engaged with the shoulder 6.

The operation of the device is simple. The piston rod 8 and the piston 7 are raised by means of the flexible element 9, the parts 7 and 8 being forced downwardly by the pull spring 18. During the ordinary pumping reciprocation of the piston 7, the release 16 does not come into contact with the latches 11; but if the release 16 is raised to the position of Fig. 4, the latches 11 are disengaged from the shoulder 6 and the piston rod 8 and associated parts can be lifted readily out of the well.

Having thus described the invention, what is claimed is:

A pump line including a cylinder, the pump line having an internal shoulder located above the cylinder, a piston mounted to reciprocate in the cylinder, a piston rod carrying the piston, a

flexible, piston-raising element connected to the upper portion of the piston rod, a guide through which the piston rod slides, a latch pivotally mounted intermediate its ends on the guide, a weight at the lower end of the latch and constituting means for swinging the upper portion of the latch outwardly, for engagement beneath the shoulder, and a latch release on the piston

rod, below the lower portion of the latch, engageable with the lower portion of the latch, upon a prolonged upstroke of the piston rod, to disengage the latch from the shoulder, and a piston-raising pull spring connected to the piston rod and to the guide. 5
